DISPLAY STAND

Henry Legler, Larchmont, N. Y.

Application June 20, 1940, Serial No. 341,415

4 Claims. (Cl. 248—160)

This invention relates to supports and the like and more particularly to a stand for displaying articles of merchandise.

One of the objects of the invention is to provide a stand of the character indicated that will remain in upright position on a counter or other surface even when pushed or brushed against and which will withstand and absorb shocks without disturbing the article displayed.

Another object is to provide a display stand of simple and economical construction which will support and hold firmly the articles to be displayed.

Still a further object is to provide a support or a display stand of the character indicated which can be adjusted to articles of different sizes.

Other objects and advantages inherent in the invention will become apparent from the following specification taken in conjunction with the accompanying drawing illustrating, by way of example, embodiments of the invention.

In the drawing:

Figure 1 is a front elevation with portions broken away of a preferred embodiment of the invention.

Figure 2 is a section taken along the line 2—2 of Figure 1.

Figure 3 is a perspective view showing the display stand shown in Figure 1 displaying two packages of cigarettes.

Figure 4 is a fragmentary view of an alternate form of clamping member for holding the articles to be displayed.

Throughout the drawing the same reference characters indicate the same or analogous parts.

The objects of the invention are carried out by attaching to a detachable base, such as a rubber suction cup or the like, a flexible stem, preferably a spring to which spring is attached a clamping frame which will hold the articles to be displayed.

Retail dealers have been reluctant to lay out articles of merchandise on a counter for display and advertising purposes for the reason that customers usually push against them and knock them down. This is a source of constant irritation to the retail dealers who usually prefer to keep the merchandise in a locker or cupboard behind the counter. The manufacturers and wholesalers thus lose the advertising consequent upon the open display of the articles on the counter.

Furthermore, display space on the counter of a store is an extremely valuable asset to any manufacturer of a small product, yet space on the counter for display purposes is limited. This particular display enables the store keeper to dis-

play products prominently on his counter yet requires counter space only the size of a small vacuum cup.

The stem being flexible causes the product to 5 sway back and forth when touched by a customer or accidentally touched by a clerk of the store thus giving the valuable asset of motion to the display.

Referring in greater detail to the drawing, the 10 detachable base is identified by the reference character 10. This detachable base consists preferably of a suction cup of conventional construction.

The spring 11, shown in Figure 1, is attached 15 to the suction cup 10 by means of a screw or bolt 12. The upper end of the spring 11 is soldered or otherwise attached to the frame generally indicated at 13.

In the embodiment shown in Figure 1, the 20 frame comprises a pair of clamping members 14, which telescope the tubular member 15. The clamping members 14 are held in their adjustable position by means of set screws 16.

The cross members 17 are formed of a single 25 wire turned upward at the bend to form a foot rest for the articles to be displayed. The cross members 17 are on an inclined position to make the articles displayed better visible. The open ends of the cross members 17 are adapted to receive an advertising tag or a price tag 18 which 30 is provided with a groove or channel 19 which accommodates the open ends of the cross member 17.

Figure 3 of the drawing shows the display 35 stand in operation. Two packages of cigarettes 20 are accommodated on a frame 13 and clamped between the clamping members 14. The suction cup 10 adheres firmly to the display counter. Because of the resiliency of the helical spring 11, the stand can be pushed about in any manner without the packages falling off.

Heretofore display stands have been used, but 40 usually they are of such rigid construction that a substantial shock will either cause the stand to become unbalanced or the vibrations will shake out the merchandise.

Figure 4 shows an alternate form of clamping 45 member. This type of clamping member operates in the manner of a turn-buckle, the screw-threaded or clamping members 21 engaging the jacket 22.

It will be understood that various other modifications may be made within the scope of the following claims.

What is claimed is:

1. A display stand comprising a suction cup for attachment to a supporting surface, a helical spring connected at one end to said suction cup and an article-supporting frame connected at the opposite end of said helical spring, said helical spring having the convolutions spaced a substantial distance apart to give substantially unrestricted flexibility in all directions.

2. A display stand comprising a suction cup for attachment to a supporting surface, a helical spring attached at one end to said suction cup, an article-supporting frame connected to the opposite end of said spring in an inclined position thereto, said frame comprising a main supporting member and a pair of adjustable clamping members extending across said main supporting member, said main member being turned upward at the lower end to provide a foot rest for the articles to be displayed and at the upper end to provide means for receiving advertising material, said helical spring having the convolutions spaced a substantial distance apart to give substantially unrestricted flexibility in all directions.

3. A display stand comprising a suction cup for

attachment to a supporting surface, a helical spring attached at one end to said suction cup, an article-supporting frame mounted on the opposite end of said helical spring in an inclined position thereto, said article-supporting frame comprising a U-bent member and a pair of adjustable clamping members across said U-shaped member, said U-shaped member being turned upward at the bend to provide a foot rest for the articles to be displayed, the legs being upturned at the ends for holding advertising signs and the like, said helical spring having the convolutions spaced a substantial distance apart to give substantially unrestricted flexibility in all directions.

4. A display stand comprising a base adapted for attachment to a supporting surface, a helical spring connected at one end to said base and an article-supporting frame connected at the opposite end of said helical spring, said helical spring having the convolutions spaced a substantial distance apart to give substantially unrestricted flexibility in all directions.
